to Standard Oil Development Company,
Elizabeth, N. J., a corporation of Delaware

Application September 1, 1950, Serial No. 182,649

5 Claims. (Cl. 196—28)

1

The present invention is directed to a method for hydrogenating a naphtha fraction containing olefins. More particularly, the invention is concerned with a method for hydrogenating a cracked naphtha containing mono- and diolefins under conditions such that the diolefins are selectively hydrogenated.

The present invention involves hydrogenating a naphtha fraction, such as a cracked naphtha, boiling in the gasoline range containing mono- and diolefins in which the cracked naphtha has added to it a small amount, in the range from 0.1% to 1.0% by weight, of a caustic soluble organic sulfur compound following which the naphtha, to which the caustic soluble organic sulfur compound is added, is contacted under hydrogenation conditions with a sulfur insensitive hydrogenation catalyst in the presence of hydrogen to cause selective hydrogenation of said diolefins to the substantial exclusion of the hydrogenation of the mono-olefins to form a hydrogenated product containing the residual organic sulfur compound and hydrogenated products of the sulfur compounds. The hydrogenated product is then subjected to treatment with a solution of alkali metal hydroxide to remove the residual organic sulfur compound and hydrogenated products of sulfur and finally the so-treated fraction is recovered for further use as may be desired.

The caustic soluble organic sulfur compound may be selected from the class consisting of the aliphatic mercaptans having from 1 to 4 carbon atoms in the molecule and the thiophenols boiling up to 450° F., the aliphatic mercaptans including methyl mercaptan, ethyl mercaptan, normal propyl and isopropyl mercaptans, normal butyl, secondary butyl and tertiary butyl mercaptans as well as the corresponding aliphatic unsaturated mercaptans, such as ethylene mercaptan, propylene mercaptan and the butylene mercaptans. By the term "thiophenols" we mean to include the broad class of thiophenols which include benzene thiol and the alkyl substituted benzene thiols boiling up to 450° F. This class of compounds, which is also caustic soluble, includes benzene thiol, the methyl benzene thiols, the ethyl benzene thiols, 2,4 dimethyl-1 benzene thiol, 2,5 dimethyl-1 benzene thiol and 2,4,6 trimethyl-1 benzene thiol.

Organic sulfur compounds selected from the aforementioned class may be added to the naphtha-containing mono-olefins and diolefins in an amount in the range between 0.1 and 1% by weight based on the naphtha. Ordinarily the

2

amount added may be in the range from about 0.1% to 0.5% by weight.

The hydrogenation conditions employed in the practice of the present invention include the employment of a sulfur insensitive catalyst, such as a catalyst illustrated by the sulfides of molybdenum, tungsten and nickel. Mixtures of the sulfides of these metals may suitably be employed. For example, a mixture of nickel and tungsten sulfide performs admirably in the process of the present invention.

Temperatures employed in the present invention may range from 400° to 600° F. with a preferred temperature being in the neighborhood of about 500° F. The pressure may be in the range from 50 to 500 p. s. i. g. or a somewhat lower pressure may be used; for example, a pressure of 45 p. s. i. g. may be employed.

Hydrogen to oil ratio may range from 100 to 2000 cu. ft. of hydrogen per barrel of feed with good results being obtained in the range from about 100 to 1000 cu. ft. per barrel. The cracked naphtha to which the organic sulfur compound has been added may be charged in contact with the catalyst at a liquid space velocity in the range from 1.5 to 12 v./v./hour with satisfactory results being obtained in the range from about 2 to 8 v./v./hour.

The invention will be further illustrated by reference to the drawing in which the single figure is a flow diagram of a preferred mode of conducting the invention.

Referring now to the drawing, numeral 11 designates a charge tank in which a cracked naphtha fraction, such as a thermally cracked or catalytically cracked naphtha, is stored. Such a naphtha fraction may contain mono- and diolefins and may have a bromine number anywhere from about 10 to 50 or more, depending on the content of the olefinic and paraffinic hydrocarbons therein. The feed naphtha is withdrawn from tank 11 by line 12 containing pump 13 and is discharged thereby into a hydrogenation zone 14. Prior to entrance into hydrogenation zone 14, the cracked naphtha has admixed with it an organic sulfur compound which is introduced into line 12 by line 15 from a source not shown. The caustic soluble organic sulfur compound is selected from the class of compounds illustrated but, for purposes of this description, will be assumed to be a relatively low boiling mercaptan, such as methyl, ethyl or butyl mercaptans. The organic sulfur compound is admixed with the cracked naphtha in an amount in the range from 0.1 to 1% by weight

and the admixture of naphtha and mercaptans discharged into hydrogenation zone 14 where the naphtha is contacted with hydrogen introduced by line 16. For purposes of this description hydrogenation zone 14 is shown as a rectangle in the drawing but it will be clearly understood that zone 14 will include catalytic reactors containing a sulfur insensitive hydrogenation catalyst as described, and means for admixing hydrogen with the naphtha and separating unreacted hydrogen and light gases which may be formed in the reaction from the hydrogenated product. Hydrogenation zone 14 may be said to include all auxiliary hydrogenation facilities well known to the art for hydrogenating naphtha fractions containing olefins.

The conditions in hydrogenation zone 14 embrace those mentioned before. The hydrogenated product is discharged from hydrogenation zone 14 by line 17 and the product will be substantially free of diolefins while the mono-olefins and the organic sulfur compound added to the said naphtha may be substantially untouched. The hydrogenation product will also include hydrogenated sulfur compounds resulting from the hydrogenation of certain sulfur compounds which may originally be present in the said naphtha. It is well known that hydrogenation will lower the sulfur content of petroleum fractions by converting certain sulfur compounds to hydrogen sulfide which may be readily removed from the hydrogenated naphtha. The hydrogenated product is admixed in line 17 with a caustic alkali solution, such as sodium hydroxide, introduced thereto by line 26. The solution of sodium hydroxide may be an aqueous or alcoholic solution of sodium hydroxide, such as a solution in methyl alcohol. Preferably the sodium hydroxide solution is an aqueous solution of sodium hydroxide having a Baumé gravity in the range of 5° to 30°. A sodium hydroxide solution having a Baumé gravity in the range of 5° to 30° gives very satisfactory results. The admixture of hydrogenated product and sodium hydroxide solution is discharged by line 17 into a settling zone 18 wherein a sufficient residence time is provided to allow separation of the sodium hydroxide treated naphtha from the sodium hydroxide solution, the treated naphtha being withdrawn by line 19 for distillation or for further treatment, as desired, and/or for use as a fuel. The used sodium hydroxide solution is discharged from settling zone 18 by line 20, controlled by valve 21 and may be discharged from the system thereby. Preferably, however, a substantial portion of the used sodium hydroxide solution is recycled to line 17 by branch line 22 controlled by valve 23 and containing pump 24 by discharging a certain amount of the used sodium hydroxide solution by manipulation of valve 21 and by introducing a sufficient amount of fresh sodium hydroxide solution by line 26 controlled by valve 25 to maintain the strength of the sodium hydroxide solution at the desired level to remove the organic sulfur compound added to line 12 by lines 15 and also to remove hydrogenated products of sulfur which may be found in the product issuing from hydrogenation zone 14.

From the foregoing description taken with the drawing it will be seen that a simple, readily adaptable process is provided for selectively hydrogenating diolefins in olefin-containing fractions.

The invention will be further illustrated by

the following runs in which a thermally cracked naphtha having an original sulfur content of 0.04 had added to it a sufficient amount of tertiary butyl mercaptan (a caustic soluble compound) and a caustic insoluble sulfur compound to provide a feed mixture having a lamp sulfur content of 0.25% by weight. The said naphtha had a bromine number of 41.6. A portion of the naphtha to which the tertiary butyl mercaptan was added was then hydrogenated by passing it in contact with a nickel sulfide-tungsten sulfide catalyst at a space velocity of 2.9 v./v./hour, a temperature of 505° F., a pressure of 45 p. s. i. g. and a hydrogen rate of 900 cu. ft. per barrel of feed. The hydrogenated product had a sulfur content of 0.043 of which the remaining tertiary butyl mercaptan content may be easily removed by contact with an aqueous solution of sodium hydroxide. The bromine number of the hydrogenated product was 33.9 while the bromine number conversion was only 18.5%. On the other hand, the conversion of diolefins as indicated by an ultraviolet absorption coefficient at a light wave length of 235 millimicrons was 88%. These results clearly show that the diolefins were substantially hydrogenated to the substantial exclusion of the mono-olefins. The sulfur conversion was 83%.

A second run was made under substantially the same conditions as the first run with the exception that the liquid space velocity was 6 v./v./hour and the hydrogen rate per barrel of feed was 780 cu. ft. In this instance the sulfur content of the feed was reduced to 0.061, the bromine number to 37.4. The bromine number conversion was 10.1% while the sulfur conversion was 76%. Again the ultraviolet absorption coefficient at a light wave length of 235 millimicrons showed that nearly 70% of the diolefins had been converted while the bromine number showed that only a slight amount of conversion of the mono-olefins had been effected. It will be seen from the second run that at the higher space velocities with less hydrogen substantial conversion of diolefins to the substantial exclusion of hydrogenation of mono-olefins was effected.

A cracked naphtha fraction treated in accordance with the present invention wherein the diolefins are selectively hydrogenated and the mono-olefins are substantially unaffected is an important tool in petroleum refining operations since the mono-olefins are very beneficial in gasoline due to their high octane numbers. On the other hand, the diolefins are very deleterious due to their inherent characteristics of reacting with oxygen and forming gum compounds. Therefore, the present invention, which selectively removes the diolefins, removes the deleterious compounds without affecting the beneficial compounds by incorporating in the feed stock to a hydrogenation process an amount of an organic sulfur compound which is caustic soluble and which may be removed from the hydrogenation products. It is only the caustic soluble organic sulfur compounds which may be effectively employed in the practice of the present invention and removed therefrom in accordance with the aforementioned description.

The nature and objects of the present invention having been completely described and illustrated, what we wish to claim as new and useful and to secure by Letters Patent is:

1. A method for hydrogenating a naphtha fraction boiling in the gasoline range containing

mono- and diolefins wherein the diolefins are hydrogenated selectively which comprises adding to said naphtha fraction a caustic soluble organic sulfur compound selected from the class consisting of the aliphatic mercaptans having from 1 to 4 carbon atoms in the molecule and the thiophenols boiling up to 450° F. in an amount in the range from 0.1% to 1.0% by weight based on said naphtha, contacting the naphtha to which the organic sulfur compound has been added with a sulfur insensitive hydrogenation catalyst at a temperature in the range between 400° and 600° F. and at a pressure between 45 and 500 p. s. i. g. in the presence of hydrogen under conditions to cause selective hydrogenation of said diolefins to the substantial exclusion of hydrogenation of said mono-olefins to form a hydrogenated product containing said organic sulfur compound and hydrogenated products of sulfur, treating said hydrogenated product with a solution of alkali metal hydroxide to remove therefrom said organic sulfur compound and hydrogenated products of sulfur and recovering said treated product.

2. A method for hydrogenating a cracked naphtha fraction boiling in the gasoline boiling range containing mono- and di-olefins wherein the diolefins are selectively hydrogenated which comprises adding to said naphtha fraction a caustic soluble organic sulfur compound selected from the class consisting of the aliphatic mercaptans having from 1 to 4 carbon atoms in the molecule and the thiophenols boiling up to 450° F. in an amount in the range from 0.1% to 1.0% by weight based on said naphtha, contacting the naphtha to which the organic sulfur compound has been added with a sulfur insensitive hydrogenation catalyst at a temperature in the range between 400° and 600° F. and at a pressure in the range between 45 and 500 p. s. i. g. in the presence of 100 to 2000 cubic feet of hydrogen per barrel of said naphtha fraction at a liquid space velocity in the range of 1.5 to 12 v./v./hour to cause selective hydrogenation of said diolefins to the substantial exclusion of hydrogenation of the mono-olefins to form a hydrogenated product containing said organic sulfur compound and hydrogenation products of sulfur, treating said hydrogenated product with an aqueous solution of an alkali metal hydroxide to remove therefrom said organic sulfur compound and hydrogenated products of sulfur and recovering said treated product.

3. A method in accordance with claim 2 in which the solution of alkali metal hydroxide is an aqueous solution of sodium hydroxide.

4. A method for hydrogenating a cracked naphtha fraction boiling in the gasoline boiling range containing mono- and diolefins wherein the diolefins are hydrogenated selectively which comprises adding to said naphtha fraction a caustic soluble organic sulfur compound selected

from the class consisting of methyl mercaptan, ethyl mercaptan, the propyl mercaptans, the butyl mercaptans, benzene thiol, the methyl benzene thiols, the ethyl benzene thiols, 2,4 dimethyl-1 benzene thiol, 2,5 dimethyl-1 benzene thiol and 2,4,6 trimethyl-1 benzene thiol, in an amount in the range from 0.1% to 1.0% by weight based on said naphtha, contacting the naphtha to which the organic sulfur compound has been added with a sulfur insensitive hydrogenation catalyst at a temperature in the range between 400° and 600° F. and at a pressure between 45 and 500 p. s. i. g. in the presence of hydrogen under conditions to cause selective hydrogenation of said diolefins to the substantial exclusion of hydrogenation of said mono-olefins to form a hydrogenated product containing said organic sulfur compound and hydrogenated products of sulfur, contacting said hydrogenated product with a solution of sodium hydroxide to remove therefrom said organic sulfur compound and hydrogenated products of sulfur and recovering said treated product.

5. A method for hydrogenating a cracked naphtha fraction boiling in the gasoline boiling range containing mono- and diolefins which comprises adding to said naphtha fraction a caustic soluble organic sulfur compound selected from the class consisting of methyl mercaptan, ethyl mercaptan, the propyl mercaptans, the butyl mercaptans, benzene thiol, the methyl benzene thiols, the ethyl benzene thiols, 2,4 dimethyl-1 benzene thiol, 2,5 dimethyl-1 benzene thiol and 2,4,6 trimethyl-1 benzene thiol, in an amount in the range from 0.1% to 1.0% by weight based on said naphtha, contacting the naphtha to which the organic sulfur compound has been added with a nickel-tungsten sulfide hydrogenation catalyst at a temperature in the range between 450° and 550° F. and at a pressure between 45 and 500 p. s. i. g. in the presence of hydrogen under conditions to cause selective hydrogenation of said diolefins to the substantial exclusion of hydrogenation of said mono-olefins to form a hydrogenated product containing said organic sulfur compound and hydrogenated products of sulfur, contacting said hydrogenated product with an aqueous solution of sodium hydroxide to remove therefrom said organic sulfur compound and hydrogenated products of sulfur and recovering said treated product.
